UNITED STATES PATENT OFFICE

DMITRI T. DUBASSOFF, OF NEW YORK, N. Y., ASSIGNOR TO R. H. MACY & CO., INC., OF NEW YORK, N. Y., A CORPORATION OF NEW YORK

DESIGN FOR A PLAYING CARD

Application filed June 29, 1929. Serial No. 31,897. Term of patent 3½ years.

To all whom it may concern:

Be it known that I, DMITRI T. DUBASSOFF, a citizen of Russia, residing at New York city, county of New York, and State of New York, have invented a new, original, and ornamental Design for Playing Cards, of which the following is a specification, reference being had to the accompanying drawing, forming part thereof.

The figure is a plan view of back of a playing card showing my new design, the opposite side being that of a conventional playing card and the novelty of my design residing in the particular type of ornamentation shown on the back.

I claim:

The ornamental design for a playing card, as shown and described.

DMITRI T. DUBASSOFF.
